United States Patent Office

Des. 177,182
Patented Mar. 20, 1956

177,182

GIRDLE

Mario Laguzzi, New York, N. Y., assignor to Poirette Corsets, Inc., New York, N. Y.

Application July 29, 1955, Serial No. 37,224

Term of patent 14 years

(Cl. D20—2)

FIG. 2.

FIG. 1.

I claim:

The ornamental design for a girdle, as shown.
